UNITED STATES PATENT OFFICE.

FRANCIS SEYMOUR, OF PATERSON, NEW JERSEY.

SPINDLE.

No. 909,465.

Specification of Letters Patent.

Patented Jan. 12, 1909

Application filed April 23, 1907. Serial No. 369,730.

To all whom it may concern:

Be it known that I, FRANCIS SEYMOUR, a citizen of the United States, and resident of Paterson, in the county of Passaic and State 5 of New Jersey, have invented certain new and useful Improvements in Spindles, of which the following is a specification.

The object of my invention is to provide a new and improved driven compound spindle which is composed of few parts, is simple in construction, perfectly lubricated and in which friction is reduced to a minimum thus permitting of running it at exceptionally high speed.

15 In the accompanying drawings, in which like letters of reference indicate like parts in all the figures: Figure 1 is a vertical sectional view of my improved compound spindle. Fig. 2 is a plan view.

20 The whirl A is made integral with the tubular spool holder B which latter is provided with a prepared wood lining C and with a wood plug D secured in the top of the spool holder, preferably by means of a 25 pin E. The spindle blade F rests loosely in a bolster or sleeve G provided at its closed bottom with a step bearing H for the spindle blade and this sleeve is inserted into a vertical tubular socket J formed on the 30 spindle holder K, said socket being surrounded by the whirl. A key L is driven into registering grooves in the interior of the socket J and the exterior of the sleeve G to hold the latter and prevent it from turning. A series of holes M extend through the walls of the sleeve or bolster G and slots N are cut through the lower part of the sleeve or bolster. The socket J is made integral with an oil receptacle O having a 35 cover P and communicating with the socket by means of a channel Q. The holder is passed through the rail R and held in place by a nut S screwed on the lower threaded end of the holder. The underside of the 40 wooden block or plug D rests upon the upper rounded end of the spindle blade and the wooden lining surrounds the upper part of the spindle loosely.

The whirl and spool holder turn or rotate on the spindle blade and the latter turns or rotates in the bolster or sleeve. The driving belt T is in frictional contact with the whirl.

Having described my invention what I claim as new and desire to secure by Letters 55 Patent is:—

1. The combination with a spindle support, of a spindle blade, the lower part of which is revolvably mounted within the spindle support and a combined whirl and spool 60 holder mounted revolvably at its upper part on the upper end of said revoluble spindle blade and supported revolvably exclusively by said revoluble spindle blade, the said spindle blade extending in one continuous 65 piece from the bottom of the support to near the upper end of the combined spool holder and whirl, substantially as set forth.

2. The combination with a spindle holder having a socket, of a bolster fixed in said 70 socket, a spindle blade mounted loosely in the bolster, a combined spool holder and whirl surrounding the spindle blade and supported on the upper end of the latter, and a wood lining in the spool holder loosely 75 surrounding the upper part of the spindle blade, substantially as set forth.

3. The combination with a spindle holder having a socket, of a bolster fixed in said 80 socket, a spindle blade mounted loosely in the bolster, a combined spool holder and whirl surrounding the spindle blade, a wood plug secured in the upper end of the spool holder and resting on the upper end of the spindle blade, substantially as set forth. 85

4. The combination with a spindle holder having a socket, of a bolster held in said 90 socket, a spindle blade mounted rotatively in the bolster, a combined spool holder and whirl, a plug secured in the upper end thereof and resting on the upper end of the spindle blade, the whirl surrounding the socket, substantially as set forth.

5. The combination with a spindle holder having a socket, of a bolster held in said 95 socket, a spindle blade mounted rotatively in the bolster, a combined spool holder and whirl, a plug secured in the upper end thereof and resting on the upper end of the spindle blade, the whirl surrounding the socket, 100 and an oil compartment communicating with said socket, substantially as set forth.

6. The combination with a spindle holder having a socket, of a bolster held in said 105 socket, a spindle blade mounted rotatively in the bolster, a combined spool holder and

whirl, a plug secured in the upper end thereof and resting on the upper end of the spindle blade, the whirl surrounding the socket, an oil chamber made integral with the 5 holder and connected with the socket by a channel, substantially as set forth.

Signed at New York city in the county

of New York and State of New York this 5th day of April A. D. 1907.

FRANCIS SEYMOUR.
